Primary Examiner — T Chase Nelson*Assistant Examiner* — Sydney Margaret Parsley(74) *Attorney, Agent, or Firm* — WPAT, P.C.(57) **CLAIM**

The ornamental design for a pergola, as shown and described.

DESCRIPTION

FIG. 1 is a perspective view of a pergola showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view of label 8 from FIG. 2;

FIG. 9 is a partial enlarged view of label 9 from FIG. 2;

FIG. 10 is a partial enlarged view of label 10 from FIG. 2;

FIG. 11 is a partial enlarged view of label 11 from FIG. 4;

FIG. 12 is a partial enlarged view of label 12 from FIG. 4; and,

FIG. 13 is a partial enlarged view of label 13 from FIG. 4.

The broken lines in FIGS. 2, 4, and 8 through 13 identify the locations and boundaries of the areas of enlargement for the partial enlarged views, and form no part of the claimed design.

1 Claim, 13 Drawing Sheets(56)
